[57] **CLAIM**

The ornamental design for a three piece plastic tube for ignition wire, as shown and described.

DESCRIPTION

FIG. 1 is a perspective view of the design in the unassembled status;

FIG. 2 is a perspective view of the design in the assembled status;

FIG. 3 is a top plan view of the design as shown in FIG. 2;

FIG. 4 is a bottom plan view of the design as shown in FIG. 2;

FIG. 5 is a front elevational view of the design as shown in FIG. 2;

FIG. 6 is a left side elevational view of the design as shown in FIG. 2;

FIG. 7 is a right side elevational view of the design as shown in FIG. 2; and,

FIG. 8 is a rear elevational view of the design as shown in FIG. 2.

FIG. 2

FIG. 3

FIG. 4

FIG. 5

FIG. 6

FIG. 7

FIG. 8
